SAFETY FUSE DEVICE

Willie A. Keen, Goldfield, Iowa

Application December 17, 1937, Serial No. 180,361

2 Claims. (Cl. 200—142)

The principal object of this invention is to provide a safety fire alarm system composed of a multiplicity of small economically manufactured fuses or contacts that, when subjected to heat, causes a bell or like signal to be operated.

A further object of my invention is to provide a safety fire alarm system whereby a great number of the contact fuses may be used in order to indicate the presence of fire soon after its origin or before the flames have done a great deal of damage.

A still further object of this invention is to provide a safety fire alarm system that is extremely economical in manufacture, durable and efficient in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

25 Fig. 1 is a schematic view of my complete fire alarm system.

Fig. 2 is an enlarged end sectional view of one of the fuses or contact points used in my system.

30 Fig. 3 is an enlarged side plan view of one of the fuse alarms more fully illustrating its construction.

There are a great number of fire alarm systems on the market. These generally consist of spraying heads and the like placed at intervals on 35 the ceilings of large buildings or other signal means consisting of a material having a low melting point placed at various intervals throughout a large building. These devices are too costly for use in homes and are subject to 40 a great deal of trouble. Furthermore, these devices are unsatisfactory as they are usually placed within the room proper. Due to the cost of these various types of systems, it is too expensive to use a great multiplicity of the units so that 45 one of the units acts as soon as the flame starts. In other words, the unit should be placed close enough together that they will act before the flames have gained much headway. I have overcome such disadvantages and objections as 50 will be appreciated and as are hereinafter more fully set forth.

Referring to the drawing, I have used the numeral 10 to designate a transformer having its primary side connected to a suitable source 55 of electric energy and having the ordinary out-

put terminals 11 and 12 on its secondary side. The numeral 13 designates an electrically actuated bell or gong and having thereon the usual electrical terminals 14 and 15 as shown. The terminal 14 of the bell 13 is connected to the terminal 11 of the transformer or like 10 by an electric lead line 16. I have used the numeral 17 to designate a lead wire having one end connected to the terminal 12 of the transformer 10 and having its other end free. The numeral 18 designates an electric lead wire having one end connected to the terminal 15 of the bell 13 and its other end free. These wires 17 and 18 extend parallel to each other and it is between these two lead lines that I place my safety fuse that I will now describe. Each of the wires 17 and 18 is bared or freed of its insulation at intervals. About this bared portion of the wires 17 and 18 is wrapped an inflammable insulative material 19 as shown in Fig. 2 of the drawing. This material can be of any type having a low flash point such as the common Celluloid. The numeral 20 designates a small spring clamp which is clamped on the outside of the material 19 as shown in Fig. 2 and which forces the wires 17 and 18 together when the material 19 has been melted or burned from between and around the wires 17 and 18. This clamp 20 may have teeth on its inner side for more securely holding the material 19 and wires 17 and 18 in the correct position and for assuring a positive contact between the wires 17 and 18 when the material 19 has been burned from about the wire. The practical operation of my device is as follows:

The terminal 11 of the transformer 10 and the terminal 14 of the bell 13 being connected with the electric lead line 16 provides one side of the source of power to the bell 13. One end of the wire 17 is connected to the terminal 12 of the transformer 10 and one end of the wire 18 is connected to the terminal 15 of the bell 13 and a plurality of the fuse elements consisting of a bared portion of the wires 17 and 18, the inflammable material 19 and the clamp 20 are imposed between these parallel lead lines. These fuses may be placed at intervals throughout the walls of a dwelling or the like and should be spaced closely together in order that the signal be sounded at the start of the conflagration. Should a fire start, the inflammable material 19 will be burned from its position about the wires 17 and 18 and the spring action of the clamp will force the wires 17 and 18 together at the point where they are bared and the clamp itself will contact the two wires 17 and 18, thereby complet- 55

ing the other side or electrical connection between the terminal of the transformer 10 and the terminal 15 of the bell or gong 13, thereby causing the alarm or bell 13 to be actuated and sounding a warning. Obviously the fuse portions 5 may be separate units and may be individually mounted and connected in the wiring circuit and, due to an extremely economical structure, a great number of these fuse elements may be 10 utilized to assure the actuation of an adequate warning device before a fire obtains a great deal of headway in the structure being protected. Thus I have provided a safety fire alarm system that fulfills my objects, overcomes the disadvantages of prior fire alarm systems and which 15 provides fuse units of small compact structure easily placed, fool-proof, and positive in operation.

Some changes may be made in the construction and arrangement of my improved safety fire 20 alarm system without departing from the real

spirit and purpose of my invention, and it is my intention to cover by my claims any modified forms of structure or use of mechanical equivalents which may be reasonably included within their scope.

I claim:

1. In a fuse for fire alarm systems, two metallic electrical conductors adjacent each other, an insulative inflammable material about said electrical conductors and a spring clamp means for holding said electrical conductors and said insulative material in position.

2. In a fuse for fire alarm systems, two metallic electrical conductors adjacent each other, an insulating meltable material about and between 15 said electrical conductors, and a spring clamp means embracing said insulating meltable material and said electrical conductors for holding them in position.

WILLIE A. KEEN. 20
